UNITED STATES PATENT OFFICE.

EDWIN C. MADDEN, OF NEW YORK, N. Y.

SAFETY-RAZOR.

1,396,645.

Specification of Letters Patent. Patented Nov. 8, 1921.

Application filed February 6, 1920. Serial No. 356,620.

To all whom it may concern:

Be it known that I, EDWIN C. MADDEN, a citizen of the United States, residing at New York, in the county of New York and State of New York, have invented certain new and useful Improvements in Safety-Razors, of which the following is a specification.

This invention pertains to safety razors and as to certain of its features is an improvement upon the construction set forth and claimed in Letters Patent No. 1,022,429 granted to me under date of April 9th, 1912. As under the former construction the present embodiment is such that an up or down stroke may be had with the cutting edge of the blade traveling in advance of the handle, a point which makes for ease of manipulation and effectiveness in operation.

Aside from this the present structure exhibits several distinct changes over the previous construction with the advantages adherent thereto and which may be enumerated as follows:

The main object of the invention is to provide an improved form of bed or supporting plate which admits of the ready placement of the blade thereon and the subsequent clamping of the blade in position by a combined swinging blade clamp and cap or cover plate.

A further object is the provision of lugs of special form which enter recesses formed at each end of the blade to engage and position the latter.

A still further object is to so mount the supporting bed or plate within the spring supporting yoke that it may, by a slight pressure rightly applied, be swung from one to another of its operative positions for shaving, or turned down into folded position, for the purpose of packing or storage within a suitable receptacle or container.

Another object resides in the provision of spring means, likewise brought about through the resiliency of the supporting yoke for holding the clamping or cap plate in its closed or open position with relation to the blade and its supporting plate.

A still further object resides in the provision of a special form of guard or comb which protects or shields the corners of the blade so as to prevent the nicking of one's face therewith. The blade which is of the double edge type, though but one edge is

exposed at a time, is provided with a pair of notches, one at each end, and likewise with an opening extending therethrough, the latter serving a double purpose, namely, to assist in the manufacture of the blade and to serve as a mark whereby the user can identify the edge which he may have used, or may have stropped for use. With these and other objects and advantages in view, as will hereinafter appear, reference will be had to the annexed drawings, wherein,

Fig. 1 is a perspective view of the razor with the blade in position for making a down stroke;

Fig. 2 a side elevation thereof with the razor in position for making an up stroke;

Fig. 3 a perspective view with the blade clamping cover plate through rearwardly and the blade exposed;

Fig. 4 a transverse vertical sectional view with the parts in the position shown in Fig. 3;

Fig. 5 a longitudinal vertical sectional view on the line V—V of Fig. 4;

Fig. 6 a horizontal sectional view on the line VI—VI of Fig. 4;

Fig. 7 an enlarged transverse sectional view on the line VII—VII of Fig. 8, of the bed or supporting plate with the blade imposed thereon, and a portion of the clamping cover plate, the latter being omitted from Fig. 8;

Fig. 8 a top plan view of the supporting plate;

Fig. 9 a side elevation showing the razor in its folded or collapsed position ready for storage;

Fig. 10 a perspective view of the supporting plate as viewed from the under side;

Fig. 11 a similar view of the clamping cover plate;

Fig. 12 a perspective view of the spring yoke which is connected to the handle; and

Fig. 13 a like view of the blade.

In said drawings 1 denotes the handle to which is secured a yoke shaped member 2, the two arms of which are alike in form and each of which is provided at its upper end with an outturned finger or pintle member 3. Each arm is preferably enlarged to a slight extent below the pintle, as at 4, and in the outer face of each enlargement there is provided or formed a socket or recess 5 formed by punching or in any suitable man-

105

110

ner. The form of the bed plate will be best understood upon reference to Figs. 4 to 8, inclusive, and Fig. 10. It may be said to comprise a bed plate proper denoted by 6, 5 which extends forwardly from and at a slight angle to a body element or cross bar 7, the latter having formed at each end thereof a wing 8 substantially semi-cylindrical in outline and standing at right 10 angles to the element 7. The forward edge of the bed plate is fashioned into a series of guard teeth 9 and the outermost tooth at each end, denoted by 10, lies in a plane slightly above the others so that they stand 15 close to the corners of the blade and prevent the corners from cutting one's face when the razor is in use. The blade 11 is of the double edge type, see Fig. 13, and is provided at its opposite ends with a notch 12, 20 the blade being likewise provided with an opening 13 located to one side of the medial line thereof, which, aside from being employed for a useful purpose in the manufacture of the blade, also serves as an index to 25 enable one to identify one or the other edge of the blade as having been used.

The bed plate 6 at each end thereof is provided with an elongated upstanding lug 14, 30 the rear edge whereof is undercut or inclined, as at 15, (see Fig. 7), the lugs entering the notches 12 and functioning therewith in a manner which will presently appear. The plate is also provided at each end with a second lug 16, said lugs being spaced apart 35 so that they engage the ends of the blade when the latter is positioned, see Figs. 2 and 6, and prevent endwise movement of the blade. The blade when positioned and clamped upon the bed in a manner presently 40 to appear, has its exposed or forward edge firmly held in proper relation to the guard teeth 9, that is, the edge is separated from the teeth by a space of nine ten thousandths of an inch, more or less, as experience dictates, but, as above noted, the outermost teeth 45 10 of the guard lie in contact, or substantially so, with the corners of the blade and thus prevent the corners from cutting or nicking one. Said end teeth are likewise 50 turned downwardly at their outer ends below the plane of the intermediate teeth 9 (see Fig. 7). Each of the wings 8 is provided with an opening 17 through which the fingers 3 pass, the combined bed plate and 55 guard (teeth 9 and 10) being thus pivotally mounted on the spring yoke 7. Each wing is likewise provided with a pair of inwardly projecting lugs or teats 18 and 19 upon the inner face thereof, which lugs are produced 60 by a punching or upsetting action, which likewise forms sockets or depressed seats 20 and 21 in the outer faces of each of the wings. Lugs 18 and 19 lie equi-distant radially from the openings 17 and are adapted 65 to enter the sockets 5 in the yoke as the bed

plate is swung to one or the other of its operative positions, Figs. 1 and 2, and to hold the plate in such positions, the spring action of the yoke securely holding the parts against accidental displacement. 70

To hold the blade in place and to protect the rear edge of the blade, I employ a combined clamping and guard element of the form best shown in Figs. 1 to 5 inclusive and Fig. 11. It may be said to comprise a 75 clamping plate 22 a rearwardly extending curved guard 23 and two arcuate arms 24, which latter are formed integrally with the plate 22 and lie at right angles thereto. Each arm adjacent each end is provided 80 with an opening 25 adapted for the reception of the pintles or fingers 3 of the yoke. Each arm is likewise provided upon its inner face with an inwardly extending lug or teat 85 26, said lugs co-operating with the sockets 20 and 21 to hold the clamping guard plate in its open or closed position. The plate 22 at each end forward of the arms 24 is provided with a thumb piece 27 by which the plate may be raised free of contact with the 90 blade and thrown from the position shown in Fig. 1 to that shown in Fig. 3. The distance between the arms 24 will be such that they make close contact with the wings 8 and the outward spring of the arms 2 of the yoke 95 holds the elements in proper adjusted position. Thus the various lugs will spring into the various sockets and will be held there owing to the pressure exerted by the yoke.

As will be best seen upon reference to 100 Figs. 4 and 7, the bar 7 is curved transversely and that the clamping plate 22 when raised or swung back stands clear thereof. This arrangement facilitates the positioning 105 of the blade 11 which is held between the thumb and forefinger and passed inwardly to such an extent that the notches 12 thereof may engage the lugs 14, the blade being then dropped upon the bed sliding forward thereon and engaging the undercut rear portion 15 of the lugs. The clamping guard is then swung forwardly, lugs 26 snapping into recesses or sockets 21 at which time the forward edge of plate 22 bears firmly upon the blade at a slight distance from the forward edge thereof. The fact that the blade engages the undercut of the lugs prevents the blade from canting or tipping as the clamp is snapped into clamping relation thereto. If for any reason the notches 12 110 should not be correctly cut so that one end of the blade would protrude farther than the other, the guard teeth 10, by reason of their formation, as above described, will prevent said edge from cutting the user. The 115 curvature of the guard 23 is such that as the part 22 is swung forward to clamping position, said guard will not contact the rear edge of the blade and will overlie and protect the same against possible injury or pre- 120 125 130

vent the user from being cut thereby. When it is desired to remove the blade the clamp may be raised by the thumb piece 27 or the clamp may be swung away from the blade 5 by applying a rearward dragging pressure upon the outer face of the guard 23 which will be roughened to afford the proper thumb grip.

As indicated in Fig. 9 the bed plate and 10 clamp may be turned inwardly and downwardly to render the structure more compact for the purpose of storage.

It is to be noted that there are no screws or screw actuated clamps present in the 15 structure either for the purpose of assembly or manipulation. The parts are readily assembled and when once assembled so remain, as there is no necessity of removal of any part for the purpose of inserting or 20 withdrawing a blade; nor for the purpose of cleansing the holder.

What is claimed is:

1. In a safety razor, a handle; a spring yoke carried thereby; oppositely disposed 25 pintles carried by the yoke; a blade supporting bed pivotally mounted on the pintles; a blade clamping member likewise pivotally mounted on the pintles; and friction connections between the yoke and bed, and between 30 the bed and clamping member serving to hold the parts in their adjusted position.

2. In a safety razor, a handle; a spring yoke carried thereby; oppositely disposed 35 pintles extending laterally from opposite sides of the yoke, said yoke having a socket formed in the outer face of each arm thereof; a blade supporting bed pivotally mounted on the pintles; a blade; a plurality of 40 pairs of lugs formed upon the bed and adapted to hold the bed in one or another angular relation to the handle; and means for holding the blade in position on the bed.

3. In a safety razor, a handle; a spring yoke carried thereby; oppositely disposed 45 pintles extending laterally from opposite sides of the yoke, said yoke having a socket formed in the outer face of each arm thereof; a blade supporting bed pivotally mounted on the pintles; a blade; a plurality of 50 pairs of lugs formed upon the bed and adapted to hold the bed in one or another angular relation to the handle; a blade clamp likewise pivotally mounted on the pintles; and means for effecting a frictional engagement between the said clamp and the bed 55 when the clamp is brought into clamping relation to the blade.

4. In a safety razor, a handle; a spring yoke carried thereby; oppositely disposed 60 pintles carried by the yoke; a blade supporting bed having a downwardly extending wing at each end thereof with an opening 65 therein to receive the adjacent pintle; a pair of lugs extending inwardly from the inner face of each wing adapted to enter a socket

formed in the adjacent face of the yoke, said wings having sockets formed in their outer faces corresponding to the lugs; a blade; a blade clamp having an arm extending downwardly from each end thereof, said arms 70 each having an opening therein through which the pintles extend; and a lug extending inwardly from each arm and adapted to function with the sockets in the wings aforesaid to hold said blade clamp in its open 75 or closed positions.

5. In a safety razor, a double edged blade; a blade supporting bed having its rear portion deflected downwardly from the plane of the body thereof; and a blade clamp having 80 a pivoted relation to said bed, said clamp having a straight blade clamping edge and a curved rear portion adapted, when the clamp is turned forward into clamping relation to a blade imposed upon the bed, to 85 stand clear of and to house the rear portion of the blade.

6. In a safety razor, a double edge blade; a blade supporting bed, said bed having its rear portion deflected downwardly from 90 the supporting plane of the bed; a combined shield and clamping element having a pivotal movement with relation to the bed, said element having a flat blade clamping forward portion and a rearwardly and downwardly curved portion adapted when the clamp is brought against the forward portion of the blade to cover and house the rear portion and edge of the blade; and means for holding the shield-clamping element in 95 its raised or lowered position with reference to the blade and bed.

7. In a safety razor, a handle; a spring yoke connected thereto; a pintle extending out from each end of the yoke; a blade supporting bed, said bed comprising a body, a cross bar at the rear portion thereof, said bar being inclined downwardly from the plane of the body, and a wing extending downwardly from each end of the bar, each 105

wing having an opening to receive the respective pintles; a pair of lugs extending inwardly from the inner face of each wing and adapted to coact with a socket formed in each arm of the yoke to hold the bed in one or another of its adjusted positions, said wing having sockets formed in their outer faces in line with the lugs; a combined clamp 110 and guard plate, comprising a substantially flat forward portion, a rearwardly and downwardly curved portion, and a pair of acute arms, each arm having an opening

therein to receive the pintles aforesaid; a lug extending inwardly from each arm, said lugs being so spaced that they will engage the 115 aforesaid sockets in the wings to hold the plate in its raised or lowered position; a pair of lugs extending upwardly, one from each end of the bed plate, the rear edges of the lugs being undercut; a double edge blade, 120

the blade having a notch in each end into which the lugs extend; a second pair of lugs extending upwardly from the bed and contacting the ends of the blade; and a plurality of guard teeth extending from the forward edge of the bed, the outermost tooth at each end lying in a place above the others

and acting to prevent the blade at the corners from cutting as the blade is drawn across the surface being shaved.

In testimony whereof I have signed my name to this specification.

EDWIN C. MADDEN.
